John A. Griswold.

UNITED STATES PATENT OFFICE.

JOHN A. GRISWOLD, OF CHICAGO, ILLINOIS.

IMPROVEMENT IN LAMP-FILLERS.

Specification forming part of Letters Patent No. 173,167, dated February 8, 1876; application filed December 28, 1875.

To all whom it may concern:

Be it known that I, JOHN A. GRISWOLD, of Chicago, in the county of Cook and State of Illinois, have invented certain new and useful Improvements in Lamp-Fillers, of which improvements the following is a full, clear, and exact description, which will enable others skilled in the art to which my invention appertains to make and use the said improvements, reference being had to the accompanying drawing, forming a part hereof, and in which—

Figure 1 is an elevation of a lamp-filler embodying my invention, and Fig. 2 a vertical central section thereof.

Like letters of reference indicate like parts. In the drawing, A represents a can, adapted to contain either oil or other burning-fluids commonly used for illuminating purposes. B is the filling-nozzle, which may be closed by a stopper, in the usual manner, as represented at *a* in Fig. 1, and C is the pouring-spout. D is an ordinary bail, by means of which the can may be carried from place to place. E is a cylinder or piston-chamber in the can. F is a piston arranged in the cylinder E, and G is the piston-stem. The stem G passes through an opening in the top of the cylinder E, and also through a close-fitting opening in the top of the can A, as shown. G' is a knob or handle on the upper end of the stem G. The lower end of the stem G is provided with a collar or flange, *b*, and *c c* are disks of packing, supported by the collar *b*. *d* is a loose disk or presser arranged above the packing, and H is a nut arranged above the presser *d*. That part of the stem G which receives the nut H is screw-threaded a distance considerably greater than that occupied by the nut, as shown. The nut H is polygonal in form, and the opening through the top of the cylinder E is correspondingly formed, and of such a size as to receive and fit the nut H when the latter is drawn upward into it by the upward stroke of the piston. The top of the cylinder E also limits the upward stroke of the piston, and the contact of the handle G' with the can limits the downward stroke. I is a tube, connecting the spout C with the lower part of the cylinder E. J is a valve, opening inwardly into the lower

end of the cylinder E, and K is a flexible tube attached to the outer end of the spout C.

The operation of the parts now described is as follows: When the piston F is drawn up the oil or burning-fluid in the can A is thereby drawn into the cylinder E, the valve J being opened by the suction and current thus produced. The free end of the tube K may then be pinched for the purpose of preventing the air from entering through it at that time; but as a rule this will be found to be unnecessary, for the upward stroke of the piston will also cause the liquid contents to enter the cylinder E through the valve J, although air may enter through the tube K at the same time. In fact, the liquid would find its level or reach the same depth within and without the cylinder E, although the piston be raised slowly enough to cause no suction. The downward stroke of the piston will close the valve J and force the liquid below the piston out through the tube I, spout C, and tube K. This flow will continue so long as the downward movement of the piston is continued, and, when the lower end of the tube K is held at a point below the bottom of the can, the flow will continue after the downward movement of the piston has ceased, for the tube K then operates as a siphon, and will drain away all the contents of the can, or as much as may be desired. By raising the tube K above the spout C, and lifting the piston slightly, the liquid will run from the said tube into the cylinder E, and thus prevent any drippings from the tube.

In order to tighten or loosen the packing, as occasion may require, I draw the piston upward until the nut H enters the socket or opening in the top of the cylinder, and then turn the piston-stem in such a direction as to either press or release the packing, thus making it run tighter or looser against the cylinder. This operation, as will be perceived, may be performed without removing any of the parts for that purpose, and when the can is closed it will also be perceived that the can need not be tipped during the operation of filling lamps, and that the contents of the can may be withdrawn with facility and without spilling the oil or fluid, thereby rendering the can or filler safe for use at all times.

Having thus described my invention, what I claim as new, and desire to secure by Letters Patent, is—

1. The combination of the can A, interior cylinder E, valve J, eduction I, stem G, support b, packing c, adjustable nut H, and the corresponding socket or opening in the top of the cylinder, substantially as and for the purposes specified.

2. The combination of the can A, cylinder

E, valve J, eduction I, flexible tube K, and a piston arranged within the said cylinder, and having a stem extending through the can, substantially as and for the purposes specified.

JOHN A. GRISWOLD.
